JOHN A. BOLANDER

BY *A. S. Pare*
ATTORNEY

UNITED STATES PATENT OFFICE.

JOHN A. BOLANDER, OF BERKELEY, CALIFORNIA.

BANJO.

Application filed December 3, 1917, Serial No. 205,017. Renewed September 29, 1922. Serial No. 591,481.

To all whom it may concern:

Be it known that I, JOHN A. BOLANDER, a citizen of the United States, residing at Berkeley, county of Alameda, State of California, have invented certain new and useful Improvements in Banjos, whereof the following is a specification.

This invention relates to musical string-instruments of the banjo or ukelele type.

- 10 The invention comprises a sound concentrator under the head of the instrument. It also comprises means for securing said head and sound concentrator in place. It further comprises a finger guard applied to 15 the angle between the finger board and the top of the rear end of the instrument. It also comprises means for securing and stretching the head of the instrument when the latter is made of skin or parchment.
- 20 The details of the invention will be described in connection with the accompanying 1 sheet of drawing, in which I have illustrated an instrument containing the invention, and in which—
- 25 Figure 1 is a perspective view of a complete instrument and shows the finger guard or stop.

Figure 2 is a longitudinal section of the rear portion of the instrument, showing the 30 means for stretching the skin head of the same, and for securing the sound concentrator in place.

Figure 3 is a similar view to Figure 2, but shows the sound concentrator and the 35 head of the instrument, both made of rigid material, such as wood.

In these figures, 1 represents the rear end of the instrument; 2, the neck or finger board and 3 a guard or stop (shown in Figure 1) 40 applied to the angle between the head and neck to prevent the fingers of the player catching upon the edge of the neck. This stop may be made of a thin piece of sheet material, of any suitable description.

45 The rear end of the instrument comprises the rim 4, which is commonly in the form of a ring, across the top of which the strings 5 are stretched. 6 represents the head of the instrument, which may be of wood, applied 50 to the rim 4, as clearly shown in Figure 3. 7 is a sound concentrator, under the head 6, which may also be made of wood, and may be glued or secured into place against the angular shoulder 8, upon the inner surface of 55 the rim. The concentrator 7, has a sound

opening 9, under the bridge 10 of the instrument. When the head 6 of the instrument is made of parchment, or its equivalent, as indicated in Figure 2, it is secured in place by doubling its edge over a wire ring 11, 60 which fits in a groove in the inner surface of the rim 4. In such a case, the sound concentrator 7, is provided with an upstanding flange or rib 12, near its edge, which is forced against the head 6, pushing it upward and 65 tightening it to any desired degree. The upward push is given by means of set-screws 13, acting against the under side of the rib 12 of the concentrator 7. These set screws pass between pairs of pins 14, which are inserted 70 in holes in the inner surface of rim 4, as shown in Fig. 2 and then bent to an approximate parallelism with the sound concentrator 7, and nuts 15 are applied thereto, resting upon the pins, thus forming a very cheap 75 and simple adjusting means for bearing upward against the sound concentrator 7. 16 represents a continuation of the edge of the sound concentrator in the form of a downward flange. 17 is a sound-reflector applied 80 to the back edge of rim 4, and extending downward and forward part way across the bottom of the rim.

The above construction results in a confined air space immediately beneath the head 85 and between it and the sound concentrator.

Having thus described my invention, and embodiments of it, I here state that I do not wish to be limited to the precise construction and arrangement of the several parts as herein set forth, as the same may be variously modified by a skilled mechanic without departing from the spirit of the invention.

What I claim and desire to secure by Letters Patent of the United States, is the following, to-wit:—

1. A banjo, comprising, in combination, a rim having an internal circular groove, a head having its surrounding edge secured in said groove, a bridge mounted upon the outer surface of said head, a sound concentrator beneath said head and a sound opening through said sound concentrator located directly beneath said bridge. 100

2. A banjo, comprising in combination, a rim having an internal groove, a head, a ring in said groove, the edge of said head being secured over said ring, a sound concentrator beneath said head provided with a downwardly projecting flange adapted to 105 110

hold said ring in said groove and means to exert an outward pressure upon said sound concentrator and thereby stretch said head.

3. A banjo, comprising a head of parchment, a sound concentrator beneath the same having its edge curved outwardly for contacting the head, and means engaging said edge for causing an outward pressure against the head and thereby tightening the same.
- 10 4. A banjo, comprising a parchment head, a sound concentrator beneath the same, provided with means for stretching the head, said means consisting of pins secured to the

inner surface of the rim, set-screws engaging said pins, and adapted to exert pressure 15 upon the sound concentrator, and nuts upon said set-screws bearing against said pins.

In testimony that I claim the foregoing, I have hereto set my hand in the presence of two witnesses, this 23, day of November, 1917.

JOHN A. BOLANDER.
